MOTHERBOARD FOR SUPPORTING AND INTEGRATING A PLURALITY OF ELECTRONIC COMPONENTS OR SIMILAR ARTICLE

Irving W. Christensen and Winston E. Bergsman, Phoenix, Ariz., assignors to General Electric Company, a corporation of New York

Filed Mar. 12, 1965, Ser. No. 84,229

Term of patent 14 years

(Cl. D26—10)

FIG. 3

FIG. 4

FIG. 5

FIG. 1 is a left side, top and front perspective view of a motherboard for supporting and integrating a plurality of electronic components, showing our new design;

FIG. 2 is a fragmentary front perspective view, to an enlarged scale, partly in cross-section taken along the line 2—2 in FIG. 1 showing the depth of the grooves;

FIG. 3 is a right side, top and rear perspective view;

FIG. 4 is a fragmentary rear perspective view, to an enlarged scale, partly in cross-section taken along the line 4—4 in FIG. 3; and

FIG. 5 is a fragmentary front perspective view, to an enlarged scale, partly in cross-section taken along the line 5—5 in FIG. 1.

We claim:

The ornamental design for a motherboard for supporting and integrating a plurality of electronic components or similar article, as shown.
